UNITED STATES PATENT OFFICE.

JAMES M. CONNEL, OF NEWARK, OHIO, ASSIGNOR TO HIMSELF AND
H. ESHBAUGH.

IMPROVEMENT IN CHAIN-PUMPS.

Specification forming part of Letters Patent No. 43,253, dated June 21, 1864.

To all whom it may concern:

Be it known that I, JAMES M. CONNEL, of Newark, county of Licking, State of Ohio, have invented certain new and useful Improvements in Chain-Pumps; and I do hereby declare that the following is a full, clear, and exact description thereof, reference being had to the accompanying drawings, making a part of this specification, in which—

Figure 1 is a vertical longitudinal section taken centrally through my improved chain-pump. Fig. 2 is a vertical transverse section through the curb-box, and also through the lower end of the shaft. Fig. 3 represents an enlarged vertical section of the metallic boxing and flaring bell-mouth at the base of the tubular shaft, and also shows the valve-seat and position of the valves as a bucket passes up between them. Fig. 4 represents the peculiar form of my bucket-links.

Similar letters of reference indicate corresponding parts in the several figures.

This invention and improvement in chain-pumps has for its object the application to the lower end of the hollow tubular shaft, through which the buckets pass as they ascend, of a metallic foot-piece, which is so constructed that it forms a boxing for embracing the lower end of the shaft, a valve-seat for the valves, a flaring tubular shell-mouth for receiving and properly centering and directing the chain in its upward movement and facilitating the influx of water into the shaft; and, finally, it serves to prevent the buckets and chain from working untrue in consequence of the wearing of the parts through long usage of the pump, as will be hereinafter described.

My invention also has for its object the construction of the valves in the tubular shaft in such manner that while they will freely open and allow the chain with its buckets to pass up through the shaft in elevating water said valves will be suddenly forced down on their seats by the reaction of the water above them, and at the same time closed tightly by one of the buckets, and thus prevent the pump-shaft from "loosing its water" when the pump is not in operation, as will be hereinafter described.

My invention also has for its object the formation of a downward-flaring throat directly above the valves, for the purpose of allowing

the latter to freely open, and also for the purpose of allowing or causing the reflux of water above the valves to spread outward and to act simultaneously upon the upper surfaces of both valves, and thereby force them down upon their seats previously to the seating of one of the buckets thereon, as will be herein-after described. Also, a novel construction of the valves and valve-seats of the pump, whereby the former are made to operate more quickly, and a substantial central bearing or support for the buckets is formed, which will allow said buckets to perfectly close the orifice through the valves when the pump is not in operation, as will be hereinafter described. Also a novel construction of the lifting-wheel, over which the chain, with its buckets, passes, whereby the former is prevented from twisting or slipping, and at the same time supports and guides are formed adapted to receive and retain the links of the chain in their proper position to allow the latter to be acted upon with the greatest advantage, and particularly to receive those links of the chain which are constructed especially for receiving and carrying the buckets, all as will be hereinafter described.

To enable others skilled in the art to make and use my invention, I will describe its construction and operation.

In the accompanying drawings, A represents the curb-box which receives the water drawn up from the well, and which also forms a support for the bearings of the lifting-wheel shaft, as shown in Figs. 1 and 2. From this curb-box proceeds downward into the well the vertical tubular shaft, through which the water is drawn by means of cylindrical blocks or buckets affixed at proper intervals to a revolving chain. This shaft B, which is usually made of wood, may be of any desired length, according to the depth of the well, and, if necessary, made up of sections properly united together, so as to increase its length. The bore or opening a, through shaft B, is suddenly enlarged at its lowermost end, so as to form a downward flaring throat and valve-chamber, b, which will be further described. Surrounding the lower end of shaft B is a metallic box, B', which may form a part of a flaring metallic extension, C, of the shaft B, as shown in Figs. 1 and 2, or, what may be

preferable, the boxing B' and the extension foot-piece C may be cast separate and then united by the flanges and bolts, as shown in Fig. 3, in which case the valve-leather can be made to form a packing by interposing it between the flanges. The metallic box B' serves as a means of securing the foot-piece C to the shaft B , and this box also serves to prevent the lower end of said shaft from swelling and leaking, while the lower flaring extension, C , forms a guard, which serves to protect the wooden shaft from the abrading action of the revolving buckets and chain. The construction of this flaring portion C is clearly shown in Fig. 1, wherein it will be seen that a circular orifice, a' , of the diameter of the bore a of the shaft B , and coincident therewith, continues down from the top of C a short distance and terminates in a flaring opening of the form of a bell-mouth, which will in practice be submerged in the water at the bottom of the well. By this form of opening it will be seen that the buckets c on the chain c' will be brought directly in a line with the bore of the shaft B as they successively enter the neck of the portion C and crowd the water into the valve-chamber b . It will also be seen that the water which is within the flaring portion of C will not have an opportunity to flow off laterally from the buckets c as they enter it and pass upward, hence the quantity of water elevated will be greatly augmented. The upper portion of the flaring foot-piece C has a depression formed in its surface which leaves two shoulders, $e e$, and in this depression the two flap-valves $g g$ are seated, so that the metallic stiffening-plates of these valves will exactly fit into the recess when said plates lie flat in their places. The thickness of these valve-plates $f f$ is exactly equal to the depth of the recess above referred to. The leather packing $h h$, which covers plates f , may by this arrangement be secured back of the shoulders $e e$, and at the same time allow the valves to fit tightly on their seats. The object of applying the stiffening-plates f on the lower surface of the leather portions $h h$ is that a leather seat will be formed for receiving the buckets c when they rest upon the closed valves and close the opening i through the center of these valves, and also to prevent the leather from drawing up and leaving an opening at the junction of the edges of the valves when they are seated. The latter object is effected by causing the valve-plates f to abut against the shoulders $e e$ as they close, and the former object is effected by making the orifice i somewhat smaller than the orifice a' or the bottom of any one of the buckets. Thus when any one of the buckets is seated upon the valves, it will be supported by the overreaching portions of plates f and the leather covering these portions. As an additional security against leakage of the valves when a column of water is pressing upon a bucket resting on them, as shown in red, Fig. 1, I have applied an annular flaring ring, j , of leather or other

suitable material, around the orifice i , the inner edges of which flare upward and serve to a great extent to center the bucket over the orifice i , and also to form a packing around the sides of the buckets when in the position above indicated. This ring is affixed to the leather portions $h h$ and split diametrically, so that each half will rise and fall with its respective valve.

The valve-chamber b , which is formed by flaring the bore a of the shaft B , is of such form (represented in Figs. 1, 2, and 3) that while it will allow the two sections of the valves to open as the buckets pass up between them, it will also allow the water above the buckets to flow down behind them and close them immediately the operation of drawing water is stopped. The entire column of water will be brought suddenly to act upon the two valves, when the upward motion of the buckets is checked, and if the crank-handle of the lifting-wheel be released the bucket immediately above the valves will descend and seat itself upon them, as above described, and stop the further flow of the water out of the shaft B , thus avoiding the loss of time and labor which would be required to raise the water from the bottom of the well at the commencement of drawing, if the pump should be allowed to "loose its water" every time it was used.

The bucket chain c' consists of a number of links united by eyes formed on the ends of each link. At every certain interval in this chain I attach a block or bucket, c , to a looped link, d , which is formed by doubling the ends of a rod of metal and then bending out the doubled ends at right angles to themselves, as shown in Fig. 4. The blocks or buckets are formed around the projecting ends, and thus held securely in place. In bending the rods to form the bucket-links it must be observed that the eyes should be at right angles to each other; and this should also be the case with the single neck-links, which are attached to the bucket-chains.

With a chain thus constructed it is necessary to make the peripheries of the driving-wheels for operating it of such form that the eyes of the links will have flat supports upon shoulders formed on one or both of the wheels, and also side or lateral supports for receiving the necks or shanks of the links and keeping the same from twisting or "kinking," and also for preventing the chain from slipping in any direction. For this purpose I construct the driving-wheel G with scallops $n n$ around its circumference arranged at regular distances apart for receiving the buckets c , as shown in Fig. 1. These scallops necessarily leave projections $p p$, each one of which has a deep groove formed in it which forms two side lips, $r r$, between which the straight portion of the link is confined. These lips flare outward, so that they will not be liable to loose the chain, and their extremities are so contacted as to leave the shoulders $s s$ on each side of them, which shoulders, together with the ver-

tical groove, receive the links and retain them in place as long as they are in contact with the wheel. The links will arrange themselves upon such a wheel in the manner represented in Figs. 1 and 2—*i. e.*, as the wheel G revolves and draws up the buckets the eyes of those links which coincide with the shoulders *s s* will be received on them, while the opposite eyes, which are at right angles to these, will fall into the grooves or bifurcations and be retained in place by the sides thereof. This form of wheel, it will be seen, is well adapted to receive the bucket-links in its grooves and on its shoulders, and to keep the double shanks of these links in their proper relative positions with the other links, while the buckets will be received in the semicircular spaces between the forked supports. The lower or guide wheel, J, is also constructed with a scalloped edge for receiving the buckets, as illustrated in Fig. 1; but instead of employing the forked lugs, as in wheel G, I score the edges of the projecting link-receiving portions *t* of this wheel J so as to form an X-groove in each, as shown in Fig. 2. This latter wheel is supported in pendent bearings F, which are secured to the side of the metallic boxing around the bottom of the shaft B, and, being let into one side of the bell-mouth C, the circumference of this wheel will keep the ascending chain in a line coinciding with the axis of the tubular shaft. The upper wheel, G, is also arranged in such relation to the bore of the shaft B as to keep the chain and buckets in a proper position therewith as they are drawn up.

Having thus described my invention, what

I claim as new and desire to secure by Letters Patent, is—

1. Applying to the lower end of a chain-pump shaft a metallic boxing, B' C, so constructed that it forms an inclosing-socket for the end of said shaft, and also an extension-guard for protecting it from wear, and for centering the buckets, substantially as described.

2. The flaring or bell-mouth metallic extension C, applied to the lower end of the tubular shaft B, and constituting the valve-seat and foot-stock of the pump, substantially as described.

3. Flaring or enlarging the lower extremity of the bore of the tubular shaft B, in combination with the valve-chamber *b* and valve *g*, substantially as described.

4. Constructing the periphery of the wheel G with laterally-forward supporting-lips and vertically-sustaining shoulders, adapted for receiving two links of a chain having eyes formed at right angles to each other, substantially as herein described.

5. The combination of the looped bucket-links *d* with a driving-wheel G, having its periphery constructed substantially as described.

6. The combination of the chain-pulley J with a metallic socket-extension, C B', which also constitutes the valve-seat of the valves *g*, substantially as described.

Witness my hand in matter of my application for a patent for improvement in chain-pumps.

J. M. CONNEL.
